CROSS

Christy M. Del Mas, New York, N. Y.

Application September 22, 1953, Serial No. 26,900

Term of patent 7 years

(Cl. D45—16)

To all whom it may concern:

Be it known that I, Christy M. Del Mas, a citizen of the United States of America, residing at city, county, and State of New York, have invented a new, original, and ornamental Design for a Cross, of which the following is a specification, reference being had to the accompanying drawing, forming part thereof.

I claim:

The ornamental design for a cross, as shown.
